SAVERIO MUCCI, OF SYRACUSE, NEW YORK.

ASSEMBLING-MACHINE.

1,163,255.

Specification of Letters Patent. Patented Dec. 7, 1915.

Application filed April 8, 1913. Serial No. 759,667.

To all whom it may concern:

Be it known that I, SAVERIO MUCCI, a subject of the King of Italy, of Syracuse, in the county of Onondaga, in the State of New York, have invented new and useful Improvements in Assembling-Machines, of which the following, taken in connection with the accompanying drawings, is a full, clear, and exact description.

This invention relates to certain improvements in machines for finishing and assembling the duplicating parts of typewriters and other machines requiring the assemblage of a multiplicity of parts, such as girders, type bars, key levers and similar elements adapted to be used in bank in a single machine. Many of these parts and particularly in typewriting machines are stamped from sheet metal and are generally provided with a series of holes either stamped or drilled therein for receiving the connections by which they are mounted in the machine or attached to other elements thereof and, inasmuch as these holes must be properly sized to a predetermined gage to establish proper fit with such connections, it is in most instances necessary to carefully ream the holes to the proper gage. At present, this reaming operation is accomplished one hole at a time by holding the part to be reamed in the hand and passing the reamer through the hole which in many instances not only causes the elongation of such hole in one or more directions as a result of the unsteady holding of the part being reamed but requires considerable time and labor to prepare and assemble the parts for a single machine.

The main object, therefore, of my present invention is to render the operation of fitting and assembling these parts more accurate and expeditious so as to materially increase the output, durability and efficiency of the completed machines and incidentally to reduce the cost of manufacture. In other words, I have sought to produce a higher degree of uniformity in milling and assembling the duplicate or similar parts of a machine so that such assembled parts may be interchanged from one machine to another with the assurance that they will fit accurately without special adjustment and will also operate with greater freedom and permanency of alignment.

Another object is to enable the machine to be applied to a wide range of uses, such as drilling, reaming, applying bolts and nuts,

and other operations where a reciprocatory motion is used in connection with a rotary motion.

A further object is to render the operation of the machine substantially automatic when once set in motion and, at the same time, to permit the reciprocating mechanism to be adjusted to move different distances toward and from the tool holders.

A still further object is to enable the speed of movement of the reciprocating mechanism to be varied at will in either direction.

Other objects and uses will be brought out in the following description.

In the drawings—Figures 1 and 2 are respectively a top plan and side elevation of a machine embodying the various features of my invention, Fig. 2 showing a portion of the legs in one end as broken away and the pedal and its supports in section; Figs. 3 and 4 are enlarged longitudinal vertical sectional views taken respectively on lines 3—3 and 4—4, Fig. 1. Fig. 5 is an enlarged transverse vertical sectional view taken on line 5—5, Fig. 1. Fig. 6 is an enlarged horizontal sectional view taken on line 6—6, Fig. 4. Figs. 7 and 8 are respectively an enlarged transverse sectional view of the machine taken on line 7—7, Fig. 1 and a longitudinal vertical sectional view taken on line 8—8, Fig. 1. Fig. 9 is a horizontal sectional view similar to but in a plane below that shown in Fig. 6. Figs. 10 and 11 are enlarged detail sectional views taken respectively on lines 10—10, Fig. 5, and 11—11, Fig. 8. Fig. 12 is an enlarged detail sectional view taken on line 12—12, Fig. 9. Fig. 13 is an enlarged detail vertical sectional view taken on line 13—13, Fig. 8. Fig. 14 is an enlarged horizontal sectional view taken on line 14—14, Fig. 2. Fig. 15 is a horizontal sectional view taken on line 15—15, Fig. 8. Fig. 16 is a transverse vertical sectional view through the upper portion of the machine taken on line 16—16, Fig. 1. Fig. 17 is a horizontal sectional view through the upper portion of the bed or frame of the machine taken on line 17—17, Fig. 2, except that the central portion thereof is broken away.

The various mechanisms forming the subject matter of this invention are mounted in or upon a main supporting frame or bed —A— and comprise broadly a tool-holder, a reciprocating work-holder movable toward and from the tool-holder, driving means for

the tool-holder, automatic means for reciprocating the work-holder, suitable mechanisms adjustable voluntarily for varying the speed and degree of reciprocatory movement of the work holder, and other devices for increasing the range of use and general efficiency of machines of this character.

Tool-holder.—The tool-holder may be used singly or in gangs according to the work required and in the present instance is employed for reaming or drilling or tapping a series of holes in the girder plates or similar parts of typewriting machines and consists of a series of revoluble tool-holding chucks —1— which are journaled on parallelism in a suitable yoke —2— on the main frame —A— and are connected for simultaneous rotation in the same direction by a train of gears —3— and a single driving spindle —4— secured coaxially to one of the gears.

The yoke —2— carrying the tool-chucks and constituting a part of the tool-holder is detachably mounted upon the main supporting frame to permit the substitution of yokes having a different number or arrangements of chucks for the reception of the same or different tools and for this purpose the yoke is arranged transversely of and above the top of the frame —A— and is supported at its ends between upright guides —5— having vertical slots —6— for receiving suitable adjusting and clamping screws —7— which are tapped into the ends of the yoke and serve the purpose of permitting the yoke to be adjusted vertically and of holding said yoke in its adjusted position. The slots —6— are preferably open at the top to permit the yoke to be easily and quickly withdrawn or replaced by simply loosening the clamping screws and retightening them. The slotted guides —5— together with the yoke —2— mounted thereon are adjustable transversely of the machine in U-shaped brackets —5'— which are rigidly secured to the top of the table —A—, said guides being held in their adjusted position by clamping screws —7'— on said brackets.

The tool-chucks —1— are shown as disposed equi-distant apart in the same horizontal plane so as to protrude from the yoke toward the work-holder presently described and are connected by spindles through suitable bearings therefor in the yoke to their respective gears —3— which are located in close proximity to the opposite side of said yoke, the hubs of the chucks and gears being slightly larger than their connecting spindles to engage the adjacent faces of the yoke and hold said chucks against endwise movement.

The gears —3— are shown as of the same size for imparting the same speed of rotation to their respective chucks and tools car-

ried thereby but it is evident that they may be of different sizes and arranged in other relations according to the nature of the work required without departing from the spirit of this invention.

The spindle —4— constitutes the direct driving means for the gears —3— but is adapted to be driven at will under variable speeds by a coaxial driving shaft —8— through the medium of a clutch —9—, said shaft being provided with a cone pulley —10— which may be connected to any available source of power to drive the shaft continuously when the machine is in operation.

The clutch —9— may be thrown into or out of action at will by means of a shift-lever —11— which is connected by link —12— to a suitable hand-lever —13— in the front side of the main supporting frame —A— as shown more clearly in Figs. 3, 5 85 and 17.

In addition to the tool spindles or chucks —1—, I have shown in Figs. 1 and 16, a pair of extra tool carrying spindles —14— as journaled in suitable bearings —15— at 90 opposite sides of and parallel with the driving shaft —8— for supporting nuts or similar elements which it may be desired to apply to certain parts as the clamping bolts for the girders previously referred to.

The bearings —15— are mounted on the upper ends of suitable screws —16— which rise from the top of the frame —A— and are adjustably secured thereto for the purpose of adjusting the bearings vertically as 100 may be required for different classes of work, or these screws and bearings may be removed and replaced by others if necessary.

The spindles —14— are provided with 105 cone pulleys —17— which are connected by belts —18— to similar cone pulleys —19— so as to drive the spindles at the same or different speeds in the same direction, the pulleys —19— being mounted on separate 110 spindles —20— beneath the top of the frame where they are journaled in suitable bearings depending from said top as shown more clearly in Figs. 1 and 16 and driven by a part of the carriage-operating mechanism 115 hereinafter described.

Work holder.—The work-holder comprises a carriage —21— which is adapted to be reciprocated lengthwise of and above the top of the main frame —A— along and upon suitable track-rails —22— and guide rods —23— toward and from the tool holder and is equipped with a jig or frame —24— and a clamping member —25— for receiving and holding the work in and upon the carriage while such work is being operated upon.

The carriage —21— preferably comprises a pair of lengthwise parallel bars —26— and cross bars —27— rigidly connecting the 130

side bars and holding them in fixed relation a distance apart corresponding to the distance between the guide rails —22— and guide bars —23—, said side bars being provided with lengthwise guide openings —28— for receiving the rods —23— and allowing the carriage to slide freely thereon. Each of the side bars —26— is provided on its underside with a pair of rollers —29— located near the ends thereof and in rolling engagement with the rails —22— to additionally support the carriage and give it greater freedom of movement. A straight toothed rack —30— is rigidly secured to the underside of the cross bars —27— midway between and parallel with the side bars —26— and forms a part of the carriage to mesh with an underlying driving pinion —31— which forms a part of the carriage feeding mechanism hereinafter described. The cross bars —27— are also provided with pendant lugs —32— forming a part of the carriage at one side of the toothed rack —30— and apertured for receiving an internally threaded sleeve —33— which extends lengthwise of the carriage and is engaged by a longitudinally extending screw-shaft —34— for adjusting the screw relatively to the tool-holder independently of the feeding means as will be hereinafter more fully described, the carriage being also provided with a longitudinally adjustable bar —35— secured to the underside of the cross bar —27— by clamping bolts —36— as shown in Figs. 7 and 8.

The guide rails —22— and rods —23— are arranged in parallelism with the axis of the tool holding chucks —1— at opposite sides of the longitudinal center of the carriage so as to support said carriage in the plane of the tool-holder and cause it to move in exact parallelism with the axis of said chucks, said guide-rails and rods being of sufficient length to allow for a maximum endwise movement of the carriage in either direction.

The guide rails and rods for the carriage are adjustable vertically to properly align the carriage and work therein with the tool-holders and for this purpose the ends of the rails —22— are supported by and between coacting pairs of adjusting screws —37— which are tapped respectively in the lower and upper sides of hollow supporting blocks —38— as shown in Fig. 4, the blocks for each rail being provided with vertically elongated open sides facing each other for receiving the adjacent ends of such rail and permitting the adjustment referred to.

The ends of the guide rods —23— are secured in the upper ends or heads of vertically adjustable screws —39— which are passed through apertures in the top of the frame —A— and are held in their adjusted position by clamping nuts —40—.

The jig —24— as shown is adapted to receive a complete set of girder plates for a typewriting machine for reaming the holes therein to a predetermined size in a single operation of the carriage by suitable reamers (not shown) which are held by the tool-chucks, it being understood that these reamers are sufficiently long to pass through the entire set of girders. This jig may be constructed to receive and align the usual spacing sleeves between the girder plates to permit the insertion of the usual tie-rods (not shown) by which the plates and sleeves are assembled after which the usual nuts may be applied to the ends of such tie rods by the spindles —14— previously mentioned, the jigs being provided with apertures for receiving the tools.

Carriage feeding means.—The pinion —31— for the carriage is secured to a cross-shaft —41— which is journaled in suitable bearings —42— on the main frame —A— (Figs. 4 and 8) and is provided with a worm-gear —43— meshing with a worm —44— on one end of a lengthwise shaft —45—. This shaft —45— is journaled in suitable bearings in the ends of a gear case —46— as best seen in Fig. 4 and is provided intermediate its ends with an axially sliding reversing clutch —47— splined thereon and having its opposite ends formed with clutch faces for alternate engagement with coacting clutch faces on the adjacent ends of coaxial sleeves —48— which are loose on said shaft so that by shifting the clutch —47— in one direction from its neutral position rotary motion will be imparted to one of the sleeves and when shifted in the reverse direction reverse rotary motion will be imparted to the other sleeve as follows.

Secured to each of the sleeves —48— are separate sets of gears —49—, those of each set being of different radii and adapted to be engaged at will by corresponding sets of separately movable gears —50— also of different radii and arranged to mesh with separate drum-pinions —51— which are secured to reversely moving coaxial shaft sections —52— as shown in Fig. 6, thereby permitting the sleeves to be rotated one at a time in reverse directions and at different speeds depending upon the gear —50— which is thrown into mesh with its corresponding gear —49— and drum pinion —51—.

The inner ends of the shaft sections —52— are journaled in a suitable hanger —53— while their outer ends are journaled in the sides of the gear case —46— and are provided with bevel gears —54— meshing with similar bevel gears —55— on the adjacent ends of rearwardly extending rotary spindles —56— which are journaled in suitable bearings on the adjacent sides of the gear case and to which rotary motion is transmitted from a lengthwise counter-shaft 130

—57— through the medium of bevel gears —58—, the latter being secured respectively to the spindles —56— and counter-shaft —57—. This counter-shaft is also journaled 5 in the sides of the gear-case —46— parallel with the main driving shaft —8— and is driven constantly by said main shaft through the medium of a chain belt —59— and sprockets —60— and —60'—, Figs. 3 and 10 16, or if a different speed is required, the belt may be shifted over onto another sprocket wheel —60''— on a parallel counter shaft —61— carrying a sprocket wheel —62— of different size which may be connected by another belt (not shown) to a sprocket —63— on the counter shaft —57—. The sprocket —60'— is loose on the main shaft —57— but is provided with a clutch face adapted to be engaged by a coaxial sliding clutch —64— which is splined on said shaft for locking said sprocket thereto when shifted to its clutching position. This shifting of the clutch —64— is effected by means 15 of a lever —65— and a link —66— connecting said lever to a pedal lever —67— of the bell-crank type, said clutch being normally held out of action by a spring-operated sliding bolt or detent —68—, (Fig. 3) in holding engagement with a shoulder —69— 20 on the link —66— against the action of a spring —70— which is connected to the lever —65— and tends to force the clutch into engagement with its sprocket —60'— and to draw the link endwise.

35 The locking bolt or detent —68— may be withdrawn at will from its locking position against the action of a retracting spring —71— of a hand-lever —72— which is fulcrumed on the main frame and extends 40 through an opening in the front side thereof as shown in Figs. 2, 5 and 7, thereby allowing the spring —70— to act in the manner described and causing the pedal end of the lever —67— to rise, whereupon the 45 locking bolt —68— will be engaged with the top of the shoulder —69—. The action of the carriage or work-holder is therefore dependent upon the position of the clutch —64— and it is evident that while the clutch 50 is engaged with the sprocket —60'—, and one of the gears —50— of each set is engaged with its corresponding gear —49— the carriage will continue to be reciprocated toward and from the tool holder to produce 55 the desired operation of the tools upon the work but if it is desired to stop the feed of the carriage at any time, it is simply necessary to depress the pedal end of the lever —67—, thereby shifting the link —66— to 60 the right hand Fig. 3 against the action of the spring —70— and withdrawing the clutch until the locking bolt rides off from the face of the shoulder —69— and is forced 65 into engagement with the side of said shoulder by the spring —71—.

The gears —50— are mounted upon the inner ends of separately movable hand-levers —75— which are pivoted at —75'— and project through apertures in the front of the frame —A— as shown in Figs. 2 70 and 5, and may be elevated at will to bring the desired gear —50— of each set into mesh with its coacting gear —49— while the other gears —50— and levers —75— remain down in their normal idle positions. 75

When the machine is in action the clutch —47— is shifted automatically in reverse directions to automatically reverse the direction of movement of the carriage and for this purpose is provided with an upright shifting lever —76— fulcrumed intermediate its ends at —77— on the hanger —53— and having its upper end engaged with the clutch and the opposite sides of its lower end engaged by suitable contact members on separate horizontal levers —78— and —79— as shown in Figs. 4, 5 and 9. The lower end of the clutch-shifting lever —76— also abuts against the adjacent end of a horizontal sliding rod —80— having its other end spring pressed against a roller contact —81— on an upright lever —82—, Figs. 8 and 9, said lever being fulcrumed at its lower end to a bracket —83— which is clamped to a stationary rod —84— having one end seated in one side of the gear case —46— and its other end secured to the lower end of a post —85— depending from the top of the frame —A—. 90

95 The upper end of the lever —82— passes through an elongated slot in the top of the frame into the path of movement of an adjustable reversing stop —86— consisting of a screw which is adjustably mounted in a bracket —87—, the latter being clamped to the adjacent screw spindle —84— on the carriage so that, when the carriage approaches the limit of its movement away from the tool-holder, as shown in the drawings, the screw stop —86— will engage and rock the lever —82— in the same direction and thereby cause its roller —81— to engage and shift the rod —80— to the right against the action of its retracting spring —80'— to engage and shift the clutch lever —76— for throwing its clutch —47— into a neutral position or out of engagement with both sleeves —48— as shown more clearly in Figs. 4 and 8 ready to be further shifted in the same direction after a greater or less interval or 100 rest of the carriage in a manner presently described. 110

115 The object in allowing the carriage to rest after being returned to the extreme limit of movement away from the tool-holders is to afford ample time for the removal of the work and the reinsertion of additional work into the jig or upon the carriage and for this purpose I have provided a slowly revolving disk —88— which, 120 125 130

in this instance, rotates approximately one revolution every 12 seconds and is provided with a circular series of separately adjustable contact members or abutments —89— centrally pivoted thereto and adapted to be adjusted from tangential positions to radial positions so that their ends will project slightly beyond the periphery of the disk, each abutment being held in its adjusted position by a separate locking bolt —90— entering a corresponding aperture —91— in the disk as shown more clearly in Figs. 9 and 12. This disk —88— is secured to an upright shaft —92— having its lower end journaled in the bottom of the gear case and its upper end journaled in the hanger —53— and provided with a worm gear —93— which meshes with a worm —94— on a longitudinally extending shaft —95— as shown more clearly in Figs. 1, 5 and 6. This shaft —95— is adapted to be driven at variable speeds from the shaft —57— and for this purpose, the latter shaft is provided with a sliding gear —96— splined thereon and adapted to be shifted by hand or otherwise into mesh with a gear —97— on the worm shaft —95— or it may be brought into mesh with one of a train of differential gears —98— for varying the speed of rotation of the worm shaft —95— and thereby varying the speed of movement of the governor disk —88—.

The use of differential gears for varying speeds in different mechanism is well known and it is therefore believed to be unnecessary to enter into a detail description of the manner of shifting these gears to produce the desired speed of rotation of the worm shaft —95— and governor disk —88— driven thereby.

I have shown the disk as provided with a series, in this instance, eight, of the adjustable abutments —89— spaced uniform distances apart circumferentially, one or more of which may be adjusted to its radial position for contact with a suitable abutment —79— on the lever —79—, thereby permitting a period of rest of the carriage in its extreme back position to be varied at will, it being understood that before the machine is started one of the abutments is adjusted by hand to produce the desired period of rest. For example, in Fig. 9, I have shown one of the abutments —89— as adjusted radially and as just about to engage and rock the lever —79— upon its pivot —m— or just after the carriage has been moved to its extreme back position, thereby causing the free end of the lever —79— to engage and shift the lower end of the clutch lever —76— to the right of its neutral position for throwing the clutch —47— into engagement with the left hand lever —48—. Fig. 4, and moving the carriage forward through the medium of the worm and gear —44— and —43— and

rack and pinion —30— and —31—. This shifting of the clutch lever —76— and its clutch —47— causes the lower end of clutch lever to engage and rock the lever —78— from its normal position, thereby throwing its contact roller, as —78— to the left, Fig. 9, where it is adapted to be engaged by a vertically movable cam —100— as best seen in Figs. 8, 10 and 11, for shifting the lever in the opposite direction when the carriage reaches the limit of its forward movement toward the tool-holders as follows: The cam —100— is secured to a vertically movable toothed rack —101— which is guided in a stationary frame —102— rising from and secured to the bottom of the gear case, said rack being secured to a vertically movable frame —103— having the lower end of one side provided with a recess —104— for receiving a detent —105— on the upper end of a lever —106— as shown in Fig. 10, said lever being fulcrumed intermediate its ends at —107— upon the post or bracket —102— and is provided with a pendant extension —108— adapted to be engaged by the adjacent end of a longitudinally movable rod —109—, the latter being guided in a lengthwise key-way in one side of the stationary rod —84—, Figs. 2, 6, 9 and 14. The opposite end of this sliding rod —109— is secured to a collar —110— which is splined on the adjacent end of the stationary rod —84— and is provided with a roller —111— adapted to be engaged by a vertically inclined cam —112— on the lower end of a vertically movable rod —113—. This vertically movable rod is guided in an upright tubular post —114—, as shown more clearly in Figs. 8 and 13, and is provided at its upper end with a roller bearing —115—, the latter being adapted to be engaged by a co-acting roller —116— on the forward end of the threaded spindle —34— as shown more clearly in Fig. 8 so that, as the carriage reaches the limit of its forward movement toward the tool-holder, the roller —116— will engage the roller —115— and depress the rod —113— against the action of a retracting spring —117—, thereby forcing the cam —112— into engagement with the roller —111— to move the sliding rod —109— endwise or to the right, Fig. 9, into engagement with an extension —108— of the lever —106—. This operation of the lever —106— releases the detent —105— from holding engagement with the back of the toothed rack —101— and allows the cam —100— to be drawn downwardly with considerable force by means of spring —118— and, as shown more clearly in Figs. 8 and 11, said cam operating on the roller —78— of the lever —78— to rock the inner end thereof against the lower end of the clutch lever —76—, and thereby throw the clutch —47— into engagement with the right hand sleeve, 130

Fig. 4, for returning the carriage to its starting position away from the tool-holder. The function of the rod —109—, therefore, is to trip the detent lever —106— when the carriage reaches the limit of its forward movement and to thereby allow the cam —100— to descend along its guide post —102— for engaging and shifting the lever —78— which in turn operates the clutch lever —76— to throw the clutch into engagement with the right hand sleeve —48—, thus returning the carriage to its starting position. This shifting of the clutch lever also forces the lever —79— into position to cause its abutment —98— to be engaged by the adjusted abutment —89— on the governor disk —88— and it is evident that, if any one of the successive abutments is adjusted for co-operation with the lever —79—, the period of rest of the carriage in its extreme back position will be increased for the purpose previously mentioned.

The cam —100— is adapted to be returned to its normal up-position in holding engagement with the detent —106— by means of a rocking toothed segment —120— journaled within the gear case and extending through the top thereof where it is provided with a roller —121— adapted to be engaged by a co-acting roller —122— on the carriage as the latter returns to its starting position, it being understood that when the cam —100— is released and is forced downwardly, the upper end of the toothed lever —120— is forced upwardly into the path of movement of the returning roller —122— which forces and rocks the lower end of the segments downwardly and thereby elevates the cam to its up-position where it is held by the detent —106—.

The operation briefly described is as follows: Assuming that the clutches —9— and —64— are in their inoperative positions and that the carriage is in its extreme back position and that the work-holder has been placed in the jig on the carriage for drilling or reaming holes in the work by the reaming or drilling tools (not shown), then the first operation is to throw the clutch —9— into action by means of the lever —18— for rotating the drilling or reaming spindles after which the clutch —64— may be thrown into action by the operation of the lever —72— which withdraws the locking bolt —68— and allows the spring —70— to act upon the clutch-operating lever —65—. Now, as soon as the active abutment —89— on the governor disk —88— engages and operates the lever —79—, the latter will engage and operate the clutch lever —76— to hold the clutch —47— into engagement with the left hand sleeve —48— to operate the carriage forwardly through the medium of the gears —49— and —50—, one of the gears —50— having been thrown into mesh

with its corresponding gear —49— by means of its hand lever —75—, thus driving the worm —44— and its gear —43— and transmitting forward movement of the carriage by means of the rack and pinion —30— and —31—. The carriage will now continue its forward movement to cause the drills or reamers to operate upon the work until the roller on the forward end of the threaded spindle —34— engages and depresses the plunger —113— whereupon the cam —112— on the lower end of said plunger will engage the roller —111— and shift the rod —109— to the right, Fig. 9, whereby tripping the detent —106— and allowing the cam —100— to descend and shift the lever —78— which in turn operates the clutch lever —76— to withdraw the clutch —47— from engagement with the left hand sleeve, Fig. 4, and to force it into engagement with the right hand sleeve for returning the carriage toward its starting position.

As the carriage approaches the limit of its return movement, its abutment —86— will engage and operate the lever —82— to shift the rod —80— endwise, thereby shifting the clutch lever —76— and its clutch —47— to their neutral positions and stopping the carriage until re-started on its forward movement by the reengagement of the active abutment —89— with the lever —79— in the manner previously described, it being understood that the time of stopping the carriage may be varied by the adjustment of the screw stop —86— and that the degree of forward movement of the carriage may also be varied by the adjustment of the screw spindle —34—.

What I claim is:

1. In a machine of the character described, a main frame, a yoke mounted upon the frame, tool-holding spindles journaled on the yoke and means for adjusting the yoke transversely of the axes of the spindles, gear connections between the several spindles for rotating them simultaneously, means for driving one of the pinions, guides on the frame parallel with the axes of the tool-holding spindles, a carriage movable along the guides toward and from the tool-holding spindles, and means on the carriage for holding a series of articles in axial alignment with the tools of the spindles.

2. In a machine of the character described, a tool-holder, a work-supporting carriage movable toward and from the tool-holder, a driving shaft, means having clutch connection with the driving shaft for reciprocating the carriage, said means including separate devices operable at will for varying the speed of movement of the carriage in one direction, and additional means also operable at will for varying the speed of movement of the carriage in the opposite direction.

3. In a machine of the character described, a main supporting-frame, a tool-holder mounted thereon, a work-supporting carriage movable lengthwise of and upon the frame toward and from the tool-holder, a driving shaft, means having clutch connection with the driving shaft for reciprocating the carriage, said means including separate sets of gears for moving the carriage in reverse directions, one gear of each set being movable at will into and out of engagement with its corresponding set.

4. In a machine of the character described, a main supporting frame, a tool-holder mounted on the frame, a work-supporting carriage movable lengthwise of and upon the frame toward and from the work holder, a driving shaft, means driven by said shaft for reciprocating the carriage and including separate sets of gears, one set for moving the carriage toward the work holder and the other set for moving the carriage in the opposite direction, one of the gears of each set being movable at will into and out of engagement with its companion gears.

5. In a machine of the class described, a tool-holder, a work-holder movable toward and from the tool holder, means for feeding the work-holder to and from the tool-holder including means for varying the period of rest of the work-holder when returned to its extreme starting position away from the tool-holder.

6. In a machine of the character described, a tool-holder, a work-holder movable toward and from the tool-holder, and mechanism for reciprocating the work-holder including means for automatically stopping the work-holder at the limit of its return movement, and additional means for starting the work-holder on its return movement after a predetermined interval of rest.

7. In a machine of the character described, a tool-holder, a carriage movable toward and from the tool-holder, means for reciprocating the carriage including reversely rotating members, a clutch movable alternately into and out of alternate connection with said members, and means operated by the return movement of the carriage for throwing the clutch to a neutral position out of engagement with both of said members.

8. In a machine of the character described, a tool-holder, a carriage movable toward and from the tool-holder, means for reciprocating the carriage including reversely rotating members, a clutch movable alternately into and out of alternate connection with said members, and means operated by the return movement of the carriage for throwing the clutch to a neutral position out of engagement with both of said members, and further means for automatically shifting the clutch into engagement with the

member for driving the carriage forwardly after a predetermined interval of rest in its starting position.

9. In a machine of the character described, a tool-holder, a carriage for holding the work movable toward and from the tool-holder, a rotary shaft, reversely rotating sleeves loosely mounted on the shaft, a clutch splined on the shaft and movable alternately into and out of engagement with said sleeves, a rotary member having adjustable clutch-operating devices, means actuated by one of said devices for throwing the clutch into operative engagement with one of the sleeves for rotating said shaft in one direction to feed the carriage forwardly toward the tool-holder, connections between said shaft and carriage for feeding the same in both directions, separate means operated by the carriage when approaching the limit of its forward movement for reversing the clutch-operating means and throwing the clutch into engagement with the other sleeve for reversing the direction of movement of the carriage, and additional means for automatically stopping the carriage when it reaches the limit of its backward movement.

10. In a machine of the character described, a tool-holder, a carriage for supporting the work movable toward and from the tool-holder, a rotary shaft, means for transmitting motion from the shaft to the carriage, additional means including separate sets of gears for rotating the shaft in reverse directions and thereby moving the carriage in opposite directions, one of the gears of each set being operable at will into and out of its active position.

11. In a machine of the character described, a tool-holder, a carriage for the work movable toward and from the tool-holder, a rotary shaft, means for transmitting motion from the shaft to the carriage, reversely rotatable sleeves on the shaft, a clutch splined on the shaft and movable alternately into and out of engagement with said sleeves for locking and releasing them to and from the shaft, an additional shaft rotating continuously in one direction, separate connections between said additional shaft and sleeves for rotating the latter in reverse directions, means actuated by the forward movement of the carriage when the clutch is engaged with one sleeve for shifting said clutch into engagement with the other sleeve to return the carriage, and additional means actuated by the return of the carriage for shifting the clutch to a neutral position out of engagement with both sleeves.

12. In a machine of the character described, a tool-holder, a carriage for the work movable toward and from the tool-holder, a rotary shaft, means for transmitting motion from the shaft to the carriage,

reversely rotatable sleeves on the shaft, a clutch splined on the shaft and movable alternately into and out of engagement with said sleeves for locking and releasing them to and from the shaft, an additional shaft rotating continuously in one direction, separate connections between said additional shaft and sleeves for rotating the latter in reverse directions, means actuated by the forward movement of the carriage when the clutch is engaged with one sleeve for shifting said clutch into engagement with the other sleeve to return the carriage, addi-

tional means actuated by the return of the carriage for shifting the clutch to a neutral position out of engagement with both sleeves, and voluntarily operated means for breaking the connections between the first named shaft and additional shaft. 15

In witness whereof I have hereunto set 20 my hand this 31st day of March 1913.

SAVERIO MUCCI.
